UNITED STATES PATENT OFFICE

LOTHAR R. ZIFFERER, OF COLUMBIA, PENNSYLVANIA

PIPE HANGER

Application filed April 26, 1929. Serial No. 358,419.

This invention relates to a method of making pipe hangers of the kind in which a ring is joined inseparably by a swivel connection to a screw-threaded sleeve adapted to depend 5 adjustably from an overhead support. In such a pipe hanger I may optionally incorporate means associated with the swivel connection for normally maintaining the ring in a fixed rotative position relative to the 10 sleeve. The production of a hanger having its two parts so related may desirably be made by casting operations, and the improvements herein set forth are directed more particularly to the steps employed in the production of the hanger components and to 15 their association one with the other in an inseparable swiveled relationship. The present invention was first disclosed in my pipe hanger application filed June 18, 1927, Serial 20 No. 199,706, of which application this is a continuation in part.

To assist in an understanding of my invention reference is made to the accompanying drawing wherein—

25 Figure 1 is a view in elevation of a pipe hanger comprising a ring which is swivelly and inseparably joined to a supporting sleeve;

Fig. 2 is a fragmentary detail showing in elevation the hanger sleeve, and in vertical 30 section a portion of the associated ring, these parts being formed for a limited relative longitudinal movement;

Fig. 3 is a similar view of the same hanger parts, showing the ring shifted to a turning 35 position upon the sleeve;

Fig. 4 is a view in elevation of the sleeve as it appears prior to the assembly therewith of the ring component;

Fig. 5 is a fragmentary sectional detail of 40 the ring component disassociated from the sleeve;

Fig. 6 which is a view similar to Fig. 2 shows a construction in which the ring is joined to the sleeve for free rotation but 45 not for relative longitudinal movement; and

Fig. 7 is a view similar to Fig. 4 of the sleeve illustrated in Fig. 6.

The pipe hanger herein shown comprises 50 a ring A having a swiveled connection with a sleeve B the internal threads 9 of which

co-operate with a depending bolt C having an overhead fastening. By rotating the sleeve the hanger may be adjusted vertically upon the bolt. A device of this character is adapted to support a pipe D which is receivable within the ring A, as shown.

The sleeve is provided by preference with a polygonal head 10 affording a convenient wrench hold. It may also have one or more transverse apertures 11 affording a view of the supporting bolt C which is threaded therewithin. A flange 12 which extends circumferentially of the sleeve provides an upper stop for a collar 14 which upstands from the ring component A. At the lower end of the sleeve is a second flange 15 providing a lower stop for the ring collar. The sleeve portion 16 between the two stop flanges constitutes a neck around which the collar is rotatable, and in the construction of Figs. 2 to 5, the neck is of sufficient length for the collar to shift vertically thereupon so as to assume either of two positions.

By reference to Figs. 2 and 3, it will be noted that the collar is provided interiorly 75 with an annular channel 17 which is open on its lower side. The upper side of this channel is defined by a shoulder 18 which is normally rested upon the flange 15. This shoulder undulates to provide teeth 19 having a form 80 and disposition for co-operation with complementary teeth 20 which upstand from the stop flange 15. When the ring is in down position, as indicated in Figs. 1 and 2, these teeth 19 and 20 interengage to oppose rotative movement of the ring upon the sleeve. The collar 14 which surrounds the neck portion of the sleeve when shifted to an upper 85 position, as indicated in Fig. 3, permits the ring to rotate freely upon the sleeve.

In the construction shown in Fig. 6, the swiveled connection between the ring and sleeve is the same as that elsewhere illustrated with the one exception that the ring collar 14^a is so related to the upper and lower sleeve 95 stops 12^a and 15^a that no appreciable relative longitudinal movement can take place. In this construction also I dispense with coacting teeth by which to resist turning movement of one part relative to the other, the ring be- 100

ing free always for rotation upon the sleeve between its two stops.

A pipe hanger answering generally to the foregoing description is particularly advantageous if its parts are made sturdy and dependable. This can be accomplished economically in a commercial way by casting the sleeve and ring from hard or white iron which is thereafter annealed. The method 5 which I pursue in this connection is to cast the sleeve, to coat the sleeve with a thin insulation 21 (see Figs. 5 and 7) preferably in a fluid condition and consisting of a suitable sand mixture in which oil or shellac may be 10 used to advantage, to dry the insulation after its application to the sleeve, to utilize the insulated sleeve as a core in the mold wherein the ring is to be cast, to cast the ring so that its collar will surround the sleeve neck, to 15 remove the insulation from between the sleeve and collar, and to anneal the hanger in its entirety—all in the order named. The operation of tapping the sleeve to provide its interior threads 9 will follow annealing of 20 the sleeve which preferably is done subsequent to casting of the ring thereon.

By proceeding according to these directions, I obtain a product which is uniformly satisfactory. The insulation is applied to 30 such portions of the sleeve as lie close to the ring collar, viz, the neck 16 and proximate faces of the two stops 12 and 15. The thickness of this insulation need be only around $\frac{1}{2}$ of an inch so that when dislodged in the finished product the amount of loose play between the ring and sleeve will be inconsequential. In addition, such a thin coating of insulation will permit the sleeve to transfer to the shoulder of the ring collar the impression of 35 any teeth which may be formed thereon, as in the construction of Figs. 2 to 5, due to the application of this insulation in a manner which preserves the form of these teeth with sufficient definiteness for the purpose stated.

An extensive experience in the production 40 of pipe hangers has demonstrated that the construction and method of manufacture herein described meets all the necessary commercial requirements. The hangers so made 45 are sturdy, require no machining of consequence, and present their two components in inseparable relation for convenience in handling and installation.

I claim:

1. The method of producing a pipe hanger 50 which consists in casting a sleeve having at one end thereof a toothed stop, in applying to a portion of the sleeve including the stop, an insulation through which the form of the 55 stop teeth is preserved, in casting around said insulated portion of the sleeve a collared ring which receives toothed impressions from the sleeve, and in removing the insulation from between these parts whereby the two 60 sets of teeth may co-operate.

2. The method of producing a two-part pipe hanger casting which consists first in forming a sleeve with spaced annular stops one of which is provided with teeth facing the other, in coating the toothed stop and adjacent portion of the sleeve with a thin insulation through which the form of the stop teeth are preserved, in casting around the sleeve a collared ring which receives toothed impressions from the toothed stop of the sleeve, and in removing the insulation from between the two castings whereby the two sets of teeth may cooperate. 70 75

3. The method of producing a pipe hanger which consists in casting a sleeve with spaced stops, in applying a thin insulation to the sleeve portion between the stops, in casting around said insulated portion of the sleeve a collared ring which takes internally the external form of the sleeve, and in removing the insulation from between these parts whereby the ring is freed for movement upon the sleeve between the stops thereof. 80 85

4. The method of producing a pipe hanger 90 formed of sections comprising casting a sleeve with a stop at the end thereof provided with spaced projections, applying a thin coating to the sleeve and said spaced projections, casting a collared ring about the coated sleeve as a core in such a manner that the collar of the ring will surround the sleeve and have formed therein spaced projections for cooperation with the projections on the sleeve for resisting relative rotative movement, and removing the coating whereby a swivel connection is 95 provided between the sleeve and collar, and the ring is freed for rotative movement upon the sleeve. 100

5. The method of producing a pipe hanger 105 formed of inseparable sections including a sleeve and a ring having an integral collar swiveled on the sleeve comprising casting the sleeve with a wrench engaging head at one end and an annular flange at its other end provided with cooperating projections on its inner side surface and an intermediate annular flange, applying a coating to the sleeve which extends from the periphery of the intermediate flange along the sleeve and over the periphery of the end flange, drying said 110 coating, casting a ring having a collar around the sleeve between the flanges thereon so that the collar receives cooperating projections from the flange on the sleeve, and removing the coating from between the sleeve and collar. 115

6. The method of making a pipe hanger 120 comprising producing a sleeve with spaced stops thereon and applying a coating to the sleeve between the stops, drying said coating, 125 casting around the coated portion of the sleeve as a core a collared pipe receiving ring which takes internally the external form of the coating, removing the coating whereby the collared pipe receiving ring is free for 130

limited longitudinal and free rotary movement upon the sleeve between the stops and subjecting the hanger to an annealing process.

In testimony whereof, I have hereunto set
5 my hand and affixed my seal this 16th day
of April, 1929.
